Attorney.

UNITED STATES PATENT OFFICE.

DAVID HOFFNER, OF BROCKTON, MASSACHUSETTS, ASSIGNOR OF ONE-HALF TO CARL E. FAHLSTROM, OF SOMERVILLE, MASSACHUSETTS.

RAILWAY.

1,289,174.

Specification of Letters Patent.

Patented Dec. 31, 1918.

Application filed July 10, 1918. Serial No. 244,133.

To all whom it may concern:

Be it known that I, DAVID HOFFNER, a citizen of the United States, and a resident of Brockton, in the county of Plymouth and 5 Commonwealth of Massachusetts, have invented certain new and useful Improvements in Railways, of which the following is a full, clear, and exact specification.

The object of this invention is the construction of an improved track rail and tie whereby the rails will be prevented from spreading, which will reduce the number of spikes needed for fastening the rail to the tie, which will automatically insure the accurate spacing of the rails, and will provide 15 certain other improvements hereinafter set forth.

My improvements consist essentially in forming each tie with an oblique notch near each end, within which the rails are seated, 20 the bottom of each rail resting upon the oblique surface of each notch, while the other surface of each notch overhangs one-half of the rail flange and thereby holds it in 25 place, the other half of the flange being held by a spike in substantially the usual manner.

In the drawings forming part of this specification, Figure 1 is a cross section of a railroad track, the tie being shown in elevation and partly in section. Fig. 2 is a cross section of a tie on the dotted line X—X in Fig. 1, a flange of the rail being shown in section. Fig. 3 is a perspective view of parts 30 of a track rail and tie. Fig. 4 is a side elevation of one part of a tie. Fig. 5 is a perspective view of the galvanized iron lining.

The ties 1 are preferably composed of wood, but may be of any type now in use, although I have illustrated them as though 40 sawed in accurately rectangular shape. This is not necessary, inasmuch as they may be of the well-known hewn form.

Near each end of the tie 1 is formed an oblique notch 2 whose surface 3 makes an angle of between twenty and thirty degrees 45 with the top of the tie, and sloping downward toward the middle of the tie. The length of this surface 3 is preferably equal to the width of the bottom 4 of the rail 5, and the face 6 of the notch is adapted in 50 angle and length to lie close over the flange 7 of the rail.

The flange 9 of the rail is confined to the tie by a spike 10 in a well known manner.

I prefer to have the web 11 of the rail rise 55 substantially vertical, and hence oblique to the rail bottom 4, thus resembling in general appearance the rails now in general use on steam roads, and also better supporting the heavy downward pressure of the wheels 60 running thereon.

For cheaper railroads, the rails may lie directly upon the surfaces 3 of the notches, as illustrated in Fig. 3, but I prefer to introduce between the rails and ties galvanized 65 iron linings 12 designed to inclose both surfaces 3 and 6 of the notches 2. This lining is formed with flanges 13, 14 adapted to fit beside the tie and to have nails 15 driven through them into the tie. The lining is 70 given additional flanges or lips 16, 17 designed to rest upon the top surface of the tie, the lip 17 being penetrated by the spike 10.

If the tie seems liable to split, a yoke or band 19 may be fastened over it at one or 75 more points, as shown in Fig. 1.

As is clear from inspection of Fig. 1, the downward pressure of a wheel 20 on a rail 5 is resisted by the oblique surface 3 of the slot or notch 2, and by the termination of the 80 notch as engaged by the edge of the rail flange 7. When the car is rounding a sharp curve and the consequent outward pressure of the wheel flange against the rail tends to overturn the latter, the notch overhang 6 85 holds the rail firmly in place.

Further, since the overhang 6 holds one edge of the rail flange down, no other fastening device is needed thereat, and hence but a single spike 10 is required for the opposite 90 flange-edge, and the number of spikes is reduced to but two for each tie.

The notches 2 being sawed in the ties before they are dumped beside the roadbed, and by a properly adjusted machine, the two 95 notches in each tie are accurately spaced, and the rails when laid therein are automatically located the required distance apart.

The lateral pressure of the wheel flange against the rail cannot cause the latter to spread, since the resultant of the downward and lateral pressures will be well within a perpendicular to the surfaces 3 of the notches.

The purpose of the metal lining 12 is two fold; its most important one is to protect 105 the wood of the ties from the rust washed down from the rails, and so to lengthen the life of the ties. A second is to help bind the

overhang 6 to the lower section of the tie and so to resist any splitting of the overhangs.

In the form of the invention illustrated in Fig. 3, the metal lining 12 is dispensed with and the rail permitted to contact directly with the wooden tie.

What I claim is:

1. The combination with a track rail having a bottom flange, of a tie therefor having a notch in its upper surface near its end, the notch having a side oblique to said surface for receiving said bottom flange, the other side of the notch overhanging one edge of said flange, and a spike driven into the tie and holding the other edge of the flange.
- 15 2. The combination with a track rail hav-

ing a bottom flange, and a web oblique thereto, of a tie having a notch in its upper surface, a side of the notch being oblique to the top surface of the tie to receive said bottom flange and support the rail with its web vertical.

3. The combination with a track rail having a bottom flange, of a tie having an oblique notch, a metallic lining fitting said notch on each side thereof, said flange resting in said lining and being overhung at one edge by one side of the notch, and a spike holding the other edge.

In testimony that I claim the foregoing invention, I have hereunto set my hand this 2nd day of July, 1918.

DAVID HOFFNER.
